UNITED STATES PATENT OFFICE.

JACOB FRED WUERTH, OF ANN ARBOR, MICHIGAN.

PIN SETTER AND SPOTTER FOR BOWLING-ALLEYS.

No. 913,797.

Specification of Letters Patent.

Patented March 2, 1909.

Application filed June 27, 1908. Serial No. 440,669.

To all whom it may concern:

Be it known that I, JACOB FRED WUERTH, citizen of the United States, residing at Ann Arbor, in the county of Washtenaw and 5 State of Michigan, have invented certain new and useful Improvements in Pin Setters and Spotters for Bowling-Alleys, of which the following is a specification.

This invention relates to pin setters and 10 spotters for bowling alleys, and has for its object the production of an apparatus having a perforated platform adapted to be raised and lowered, and having certain features and attachments of special construction and 15 particular arrangement, by which it is believed the pins may be more promptly and accurately set upright and spotted than is practicable with any other like apparatus with which I am acquainted.

20 The stated object is accomplished by fashioning and associating parts as illustrated in the accompanying drawings, of which—

Figure 1 represents a front view of all parts assembled. Fig. 2 is a front view of one of 25 the pin-raising prongs by itself. Fig. 3 is a top plan view of the movable perforated platform, and Fig. 4 is a vertical section of the platform upon line x—x of Fig. 3.

Like characters are used to refer to the 30 same parts throughout the drawings and specification.

The letter A marks the floor of the alley, and B the ceiling of the room, above it. At the sides of the alley are the customary 35 channeled walls 1 and 2, and brackets 3 and 4 are secured to those walls. The brackets support the vertical guide tubes 5 and 6 which have their upper ends fixed to the ceiling B as shown. Movable up and down 40 within the guide tubes are the relatively smaller tubes 7 and 8 which are attached by means of the fittings 9 and 10 to the perforated platform 11. Rising from the platform and curving toward each other are the 45 arms 12, 13 and 14. The platform is normally held in its raised position by the weights 15 and 16 to which the rope 17 is tied at its ends. The rope passes under the pulley 18 which is rotatively attached to 50 block 19, and the rope also passes over the pulleys 20 and 21 secured to the ceiling B at the sides or adjacent to the ends of the guide tubes 5 and 6 already mentioned. It may be here stated that the upper ends of the 55 arms 12, 13 and 14 are attached to the block

19 by which connection, therefore, the platform is upheld. The cords 22 and 23, shown in Fig. 1, extend in opposite directions and are tied to the weight rope 17. The cords have a common junction 24 with the draw 60 rope 25.

Considering Figs. 3 and 4 it will be noted that the platform has a number of circular perforations 26 bounded in part by a semi-cylindrical wall 27. The wall extends both 65 above and below the platform, as illustrated in Figs. 1 and 4. Again considering Figs. 3 and 4 it will be noted that one side of each perforation or opening 26 is extended in a recess 28 formed in the upper surface of the 70 platform, and the bottom of the recess is shown to be downwardly inclined toward the opening 26. Flat springs 29 are attached to the walls 27 within the openings 26, and these will be further mentioned.

The pin-raising members, as best shown in 75 Fig. 2, comprise the base block 30, the shank 31, and the prong 32. The shank 31 passes upwardly through the platform and the prong is located in the inclined recess 28. 80 The base block 30 hangs below the platform, and maintains the shank 31 in a vertical attitude.

The operation of this invention may be thus explained—Let it be assumed that the 85 pins have been all overturned and are to be reset. The attendant picks up the pins and places each upon the platform with its butt toward an opening 26 and its neck resting in the recess 28, as indicated by the broken 90 lines in Fig. 4. Then he draws upon rope 25, with the result that the weights are raised, the platform descends, and the base blocks 30 of the pin-raising elements come into contact with the floor of the alley A. The prongs 32 95 raise the necks of the pins and their bodies slip into the openings 26 and between the light flat springs 29 which serve to accurately center the pins in the openings and upon their respective spots. The descent of the 100 weights lifts the platform from the pins. The actual setting and spotting of the pins is, therefore, accomplished without touching any pin with the hand, and no question of unfairness in positioning the pins can arise.

Having now described my invention and 105 explained the mode of its operation, what I claim is—

1. In a pin setter and spotter, the combination with a movable platform having open- 110

ings, of hand-operated means for raising and lowering the platform, each of said openings being provided with a semi-cylindrical wall, pin-raising members each having a shank 5 passing movably through the platform and a prong located upon the upper end of the shank and upon the opposite side of the opening from the said wall, and a base block attached to the shank below the platform, substantially as described.

2. In a pin setter and spotter, the combination with a movable platform having openings, of hand-operated means for raising and lowering the platform, each of said openings 15 being provided with a semi-cylindrical wall on one side and a recess on the other side formed in the surface of the platform, pin-raising members each having a shank passing movably through the platform and a prong 20 upon the upper end of the shank and located in the said recess, and a base block attached to the said shank below the platform, substantially as described.

3. In the pin setter and spotter, the combination with a movable platform having openings, of hand-operated means for raising and lowering the platform, each of said openings being provided with a semi-cylindrical wall extending above and below the plat-

form, pin-raising members each having a shank passing movably through the platform and a prong upon the upper end of the shank and located upon the opposite side of the opening from the said wall, and a base block attached to the shank below the platform, substantially as described.

4. In a pin setter and spotter, the combination with a movable platform having openings, of hand-operated means for raising and lowering the platform, each of said openings 40 being provided with a semi-cylindrical wall, pairs of springs one pair being secured to the wall in each opening and the springs of each pair being secured on opposite sides of the opening whereby a pin may be centered within the opening, pin-raising members each having a shank passing movably through the platform and a prong upon the upper end of the shank and located upon the opposite side of the opening from the said wall, and a 50 base block attached to the shank below the platform, substantially as described.

In testimony whereof I affix my signature in presence of two witnesses.

JACOB FRED WUERTH.
